UNITED STATES PATENT OFFICE.

WALTER H. UTTERBAUGH, OF WASHINGTON, DISTRICT OF COLUMBIA.

LOCOMOTIVE DRIVING BOX.

Application filed December 20, 1924. Serial No. 757,233.

This invention relates to new and useful improvements in locomotive driving boxes.

The primary object of the invention is to provide a locomotive drive box of such a construction that the act of renewing wearable parts thereof may be classed with the light work repairs instead of being in the heavy work class as heretofore.

A further object of the invention is to provide a construction of the above mentioned type which will permit the removal of the driving box, the wear shoes, the lateral thrust wear face member, the lubricant cellar, and the bearing brass without taking down or dropping the driving wheels, disturbing connecting rods or brake rigging, or taking down the pedestal binder.

Other objects and advantages of the invention will be apparent during the course 20 of the following description.

In the accompanying drawings forming a part of this specification and in which like numerals are employed to designate like parts throughout the same,

25 Figure 1 illustrates an elevational view, with the driving axle in vertical section, of the locomotive drive box embodying this invention properly associated with the locomotive pedestal frame and spring supporting structure,

30 Figure 2 is a horizontal sectional view taken upon line II-II of Fig. 1.

Figure 3 is a horizontal sectional view of the structure shown in Fig. 1,

35 Figure 4 is a horizontal sectional view illustrating the driving box shifted laterally inwardly along the driving axle for permitting the removal of the wear shoes, one of which is shown entirely removed from the pedestal frame and the remaining wear shoe shown in full lines and dotted lines for indicating the manner of removing the same,

40 Figure 5 is a vertical sectional view taken upon lines V-V of Fig. 1,

45 Figure 6 is a side elevational view of the driving box embodying this invention with the removable outer flange disconnected therefrom,

50 Figure 7 is a front elevational view of the removable outer flange shown in detail, and

55 Figure 8 is an edge elevational view of the removable outer flange shown in Fig. 7.

In the drawings, wherein for the purpose of illustration is shown a preferred embodiment of this invention, the numeral 5 design-

nates the pedestal frame having the spaced vertical legs 5^a which form the space 6 for the reception of the driving box and the box wear shoes to be described at a later point. Suitably, removably connected to the pedestal frame 5 is the pedestal binder 7 which forms the bottom wall of the space 6. The drive box has resting thereupon the spring saddle 8, which is of substantially inverted U-shape, having the spring structure 9 pivotally mounted thereupon. Suitably connected to the outer ends of this spring structure 9 are the spring hangers 10 which have pivotally connected to their lower ends the equalizers 11. The connection of a locomotive to the equalizers 11 is well known in the art and no explanation or illustration of the same is deemed necessary.

In Figs. 1 to 4 inclusive, the legs 5^a of the pedestal frame are illustrated as having associated therewith the box wear shoes 12 which are of substantially U-shape in cross-section and are primarily retained in place either by a friction fit with the legs 5^a or by the drive box which is positioned therebetween. The drive box, as depicted in detail elevation in Fig. 6 and in various sectional views in Figs. 1 to 5, may be described in detail as comprising a body portion 13 of substantially rectangular formation in vertical section and having an integrally formed inner flange 14. The outer end portion of this body 13 is of generally reduced dimensions and has formed therein the inverted U-shaped groove 15 which extends across and down both sides of the reduced end portion previously referred to. The body portion 13 has formed in its upper face a saddle seat 16 which is arranged in juxtaposition to the integral inner flange 14 and is formed in the bottom wall of the cutout portion or depression 17 formed in the said top of the body 13. The bottom wall of this cutout portion or depression 17 is further provided with a horizontally elongated pocket 18 which communicates with the groove 15.

In the various figures, the driving box is illustrated as being cut away for the reception of the bearing brass 19 which is interposed between the box and the driving axle 20. Located below the driving axle and within the cutout portion of the driving box is the lubricant cellar 21. The manner of retaining this lubricant cellar in place will be described at a later point.

Illustrated in detail in Figs. 7 and 8 is the substantially inverted U-shaped removable outer flange 22 which has formed on its inner edge an inverted U-shaped rib 23 which extends the entire length of the said edge and is of a suitable size to be snugly received within the groove 15 formed in the reduced end portion of the body 13 of the driving box. This removable outer flange 22 is further provided with a laterally projecting, lateral wearing face 24 which conforms in shape generally with the shape of the flange 22 and rib 23. Carried by the upper portion of the inner face of this flange 22 is a horizontally elongated boss 25 which has formed in its upper face a longitudinally extending saddle 26.

When the various parts are assembled, it will be noted that the wear shoes 12 are received upon the pedestal frame legs 5^a and the body portion 13 of the driving box is arranged therebetween and in engagement therewith, the length of the space 6 between the legs 5^a permitting, however, vertical sliding movement of the box between the upper portion of the pedestal frame 5 and the pedestal binder 7. The inner, integral flange 14 on the box body 13 will prevent outward removal of the box from the pedestal frame, and the positioning of the outer flange 22 with its rib 23 received within the groove 15 will prevent the inward movement of the driving box in respect to the pedestal frame. The bearing brass 19 is properly arranged between the inner face of the body of the box and the lubricant cellar 21 may then be properly located. To retain the cellar 21 in position and to prevent unintentional removal of the flange 22, a transversely extending locking pin or bolt 27 is passed through suitable openings formed in the lower ends of the flange 22, and the body portion 13 of the driving box and also through the lower portion of the lubricant cellar 21 and is retained in place by any suitable means, such as a cotter pin 28.

It will be noted that when the removable flange 22 is assembled in respect to the body portion 13 of the driving box, the rib 23 will be received within the flange 15 of the box and the horizontal elongated boss 25 will snugly fit within the horizontally elongated pocket 18 formed in the body portion 13. In Figs. 3 and 5, the lower ends of the spring saddle are illustrated as respectively resting in the saddle seats 16 and 26 of the body portion 13 and boss 25. The weight of the locomotive, not illustrated, upon the spring saddle 8 will further aid in preventing unintentional removal of the flange 22 in view of the fact that the saddle 8 rests directly upon the boss 25 of this flange.

The manner of renewing the various

wearable parts of the driving box embodying this invention will now be described. When it becomes necessary to renew a bearing brass or wear shoes, the weight of the locomotive upon the spring 9 and saddle 8 should be removed and the said spring and saddle shifted to free the saddle from its position upon the driving box and flange boss 25. The locking pin or bolt 27 should then be removed which will permit the withdrawal downwardly of the lubricant cellar 21. The outer removable flange 22 should then be withdrawn vertically after which the driving box may be shifted laterally inwardly along the driving axle 20, as illustrated in Fig. 4. The box may then be easily disconnected from the axle 20 by merely lifting the same vertically. In Fig. 4 the simple manner of removing the wear shoes 12 is clearly illustrated and is made possible after the drive box has been shifted laterally inwardly along the axle 20. The manner of assembling these various elements to return the locomotive to an operative condition will, of course, be clearly understood from the drawings and above detail description.

The removable flange 22 has been described as possessing an integrally formed laterally extending, lateral wearing face 24. This wearing face is intended to receive the lateral thrust and wear caused by the engagement therewith of the drive wheel 29. The wearing away of this face 24 will of course make necessary the renewal of the same. Such renewal may be easily accomplished by merely withdrawing the locking pin or bolt 27, after the weight of the locomotive has been removed from the spring 9 and saddle 8, and the flange 22 with the said surface 24 removed for permitting metal to be deposited, as by a welding operation or the like, upon the surface 24 for building up the same to a proper thickness. The said surface may then be planed and the flange is ready to be replaced.

It is now believed that the construction and manner of assembling the various elements embodying this invention and the advantages derived from constructing and assembling the same in the manner described will be readily understood and appreciated from the above detail description. It is to be understood, however, that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In a device of the type described, a drive box, an integral flange at one end

thereof, the remaining end of the box being of reduced inverted U-shape and having an unbroken groove formed across the top and down the full length of both sides thereof, 5 the top of the main portion of the box having a horizontally elongated pocket provided therein with the intermediate portion of its bottom wall formed as an extension of the bottom wall of the top part of said 10 groove and with the ends projecting laterally of these registering walls, and a removable flange carried by the reduced end of the box, said removable flange having a continuous rib received in the groove and a 15 horizontally elongated boss received in said pocket and extending the full length of the same, the tops of the drive box and the horizontally elongated boss having spring saddle receiving seats formed therein.

2. In a device of the type described, a 20 drive box, an integral flange at one end thereof, the remaining end of the box being of reduced inverted U-shape and having an unbroken groove formed across the top and down both sides thereof, the top of the main 25 portion of the box having a horizontal pocket provided therein with its bottom wall formed as an extension of the bottom wall of the top part of said groove, and a removable flange carried by the reduced end 30 of the box, said removable flange having a continuous rib received in the groove and a horizontal boss received in said pocket, the top of the boss having a spring saddle receiving seat formed therein. 35

In testimony whereof I affix my signature.

WALTER H. UTTERBAUGH.
